SEPARABLE FASTENER

Davis Marinsky and Louis H. Morin, Bronx, N. Y.

Application April 22, 1942, Serial No. 439,984

14 Claims. (Cl. 24—205.5)

This invention relates to separable fasteners employing stringers coupled and uncoupled by a slider movable along the stringers and more particularly to a special form of automatic lock for retaining the slider against movement along the stringers in which a lock member on the slider is made to engage with the links or scoops at portions other than the exposed sides thereof. The novel features of the invention will be best understood from the following description when taken together with the accompanying drawing, in which certain embodiments of the invention are disclosed, and in which the separate parts are designated by suitable reference characters in each of the views; and in which:

Fig. 1 is a sectional view through a slider arranged upon the stringers of a separable fastener showing the slider in locked position.

Fig. 2 is a partial section on the line 2—2 of Fig. 1.

Figs. 3 and 4 are views similar to Fig. 2 showing the slider in two different unlocked positions.

Fig. 5 is a perspective view of a link or scoop detached.

Fig. 6 is a perspective and sectional view of the slider detached; and

Fig. 7 is a perspective view showing a modified form of link or scoop which is employed.

In the construction of separable fasteners of the kind under consideration employing sliders having locking means for retaining the slider against movement along the stringers, it has been the common practice to arrange the locking pins or elements in a position to ride over upper or outer surfaces of the links or scoops. When these are plated or coated, the lock pins or elements tend to mar or deface the stringers. Furthermore, with the conventional type of locking means, the lock element engages the comparatively narrow edge of the link or scoop which produces an uncertain locking engagement.

It is the purpose of our invention to overcome the above and other objectionable features to the conventional type of lock slider construction by mounting on the slider a locking member, preferably spring-actuated, which will engage a link or scoop at a point between its two sides.

In the illustrative form of our invention shown herein, the slider is provided with a transverse bar yoke, or what might be termed a "whiffle tree," yieldingly supported in the cross web or frog of the slider and arranged to contact with the outer end of a scoop, this outer end preferably being provided with a projection to insure a better locking engagement between the yoke

and the scoop. Either one or both of the ends of the transverse bar yoke may extend through the corresponding wall of the slider and be provided with a pull tab so that a pull on either pull tab will not only move the slider, but will automatically release the lock. This provides a strong and positive lock for the slider which will not mar or deface the outer visible surfaces of the links or scoops and one which may be released from either side of the slider.

In Fig. 1 of the drawing, 10 represents the stringer tapes, 11 the links or scoops attached to the beaded edge 12 of the tapes. The slider employed for coupling and uncoupling the stringer tapes is shown at 13.

Each link or scoop comprises a yoke-shaped mounting end portion 14 arranged upon the beaded edge 12 and a coupling end portion having a projecting knob 15 on one side, and a recess or socket 16 on the other side, to receive the knob 15 of the link or scoop of an opposed stringer. The outer end of the coupling end portion has a projecting substantially hook-shaped member or nose 17 preferably of a width slightly less than the width of the link or scoop, as clearly seen in Fig. 5 of the drawing and the upper surface of this nose, where it joins the bevelled outer surface 18 of the scoop, forms a recess or pocket 19 adapted to receive the coupling element 20 of the slider 13.

The element 20, in the construction shown, is in the form of a bar yoke or what might be termed a whiffle tree. The element 20 operates in elongated apertures 21 formed in opposed side walls 22 of the slider, the apertures extending into the web or frog 23 which joins the walls 22 centrally of the wide end of the slider, as is clearly illustrated in Fig. 6 of the drawing. The frog 23 also has centrally and longitudinally thereof an enlarged bore 24 in which is arranged a coil spring 25. The spring 25 seats upon one edge of the element 20 and around a projecting tongue 26 on said edge. The other edge portion 27 of the element is adapted to engage the nose 17 and to seat in the recess 19, as is clearly illustrated in Fig. 1 of the drawing.

In the construction shown, the element 20 projects beyond both walls 22 of the sliders, which adapts the sliders to the dual use of operation from either side of the fastener. However, where this is not essential, the element will project from one side only. The projecting ends of the element 20 have finger pieces or pull tabs 28 coupled therewith, these pull tabs being pivoted on

the projecting ends of the element in order to swing toward either end of the slider.

The spring 25 normally holds the element 20 in the locked position, as seen in Figs. 1 and 2 of the drawing. In moving the slider along the stringers to uncouple the same, the element 20 will be moved into the position shown in Fig. 3, the pull on the finger piece 28 being in the direction of the arrow X of said figure, whereas in coupling the stringers, the finger piece is pulled in the direction of the arrow X2 of Fig. 4. In both of these operations, the element operates in the manner of a whiffletree. It will be understood that the elongated slots or apertures 21 are of sufficient length and so arranged as to not only disengage the element 20 from the projecting nose 17, of the scoop of each stringer, but also out of the path of the scoops in passing into and out of the diverging channels at the wide end of the slider.

For purposes of description, the end 29 of the element will be regarded as the inner end and the end 30 the outer end. In the normal position of the element, as seen in Fig. 2, these ends are arranged in transverse alignment with the element seating on the end wall 31 of the apertures 21. In operating the finger piece, as shown in Fig. 3, the end portion of the element 30 pivots on the wall 31, thus throwing the other end 29 in the direction of the wall 32 of the aperture 21; whereas in operating the element, as shown in Fig. 4, the end 29 seats on the wall 31 and the end 30 is moved into engagement with the wall 32. Both angular positions of the element, illustrated in Figs. 3 and 4 of the drawing, will provide free passage of the links or scoops through the slider. It will, of course, be apparent that upon releasing the pull on the finger piece, the spring 25 will automatically return the element to the locked or normal position, as illustrated in Fig. 2 of the drawing.

It will, of course, be apparent that the invention is applicable to links of any type and construction, so long as the structure of the link is such as to provide a part with which the lock member will engage. In Fig. 7 of the drawing, the principle of the invention is shown applied to what is termed a double acting link or scoop, that is to say, a link or scoop having two similar or identical coupling side surfaces each having male and female coupling portions. This double acting link or scoop is identified generally by the reference character 33. The mounting end portion 34 of the scoop is yoke-shaped in form and the coupling end portion 35 is provided on opposite surfaces with substantially triangular projecting coupling portions 36 inwardly of which are recesses 37 to receive the portions 36 of opposed scoops. The recesses 37 have key elements 38 centrally thereof adapted to enter channels 39 formed in the outer surfaces of the scoops. At the outer end of the scoops and projecting in the direction of the upper and lower surfaces thereof are pairs of members 40 equivalent in all respects to the member 17 with the exception that they are arranged adjacent side surfaces of the scoops 33; rather than being arranged centrally of the scoops, as seen in Fig. 5 of the drawing.

With the construction shown in Fig. 7, it will be apparent that the lock element of the slider, depending upon the position of the slider on the stringers, can operate upon either pair of members 40.

Upon a consideration of Fig. 1 of the drawing, 75

it will be understood that in the event of a stress or strain applied to the stringers 10, tending to separate the same, the element 20 will force the engaged link or scoop 14 upon the next adjacent link or scoop, thus definitely blocking further movement of the slider and producing a positive lock thereof even to the degree of movement of the element from the position shown in Fig. 2 to a position where the element engages the wall 32 assuming that such movement were possible in an excessive stress or strain.

The bar-like lock element actually forms an extension to the contracted inner end of the web or frog of the slider. This element projects in the manner of a fin to provide a block for the free passage of the links or scoops through the slider, particularly with respect to engagement with the hook-shaped projections employed. Furthermore, this element may be said to comprise a blocking element arranged at the intersection of the diverging channels of the slider.

Having fully described our invention, what we claim as new and desire to secure by Letters Patent, is:

25 1. The combination with a channeled slider body having diverging channels at one end thereof, of a spring actuated lock element traversing the channel of the slider at the intersection of said diverging channels means for mounting said locking element to permit longitudinal movement thereof in relation to said slider, stringer scoops movable through the channels of said body in coupling and uncoupling scoops of opposed stringers by movement of the slider longitudinally thereof, outer extremities on said scoops having projecting members adapted to engage the lock element of the slider in automatically checking movement of the slider in one direction on said stringers, and means whereby said element may be moved out of engagement with the projecting members of said scoops in operating the slider longitudinally of the stringers.

45 2. The combination with a channeled slider body having diverging channels at the wide end thereof, converging to a single channel at the narrow end thereof, of a lock element normally blocking the channel at the intersection of said diverging channels, resilient means normally urging said element longitudinally of the slider and holding said element in blocking position, and means whereby said element may be moved against the action of said resilient means into unblocking position.

50 3. The combination with a channeled slider body having diverging channels at the wide end thereof, converging to a single channel at the narrow end thereof, of a lock element normally blocking the channel at the intersection of said diverging channels, resilient means normally supporting said element in blocking position, means whereby said element may be moved against the action of said resilient means into unblocking position, said element comprising a bar having end portions projecting from both side walls of the slider, and the slider having an elongated channel in which said bar is freely movable longitudinally of the slider.

60 4. The combination with a slider having a lock element to engage the scoops of stringers in retaining the slider against movement in one direction on the stringer, of a stringer scoop comprising a mounting end portion and a coupling end portion, and the outer extremity of the coupling

end portion of said scoop having a projecting hook-shaped nose adapted to engage the element of the slider in checking movement of the slider on the stringers.

5. A scoop device for stringers of separable fasteners employing lock sliders movable along the stringers, said scoop comprising a mounting end portion and a coupling end portion, said coupling end portion having male and female elements providing interengagement of scoops of opposed stringers, and the outer extremity of the scoop having a projecting slider locking nose.

6. A scoop device for stringers of separable fasteners employing lock sliders movable along the stringers, said scoop comprising a mounting end portion and a coupling end portion, said coupling end portion having male and female elements providing interengagement of scoops of opposed stringers, the outer extremity of the scoop having a projecting slider locking nose, and said nose being arranged within the limits of side surfaces of said scoop.

7. A lock slider for separable fasteners, said slider comprising a channeled body having walls spaced at the wide end of said body by a connecting frog forming diverging channels at the wide end of said body, a lock element movably supported in the frog of said slider to extend into the channel thereof at the intersection of said diverging channels, and a spring mounted in the slider and engaging said element to normally hold the said element in projected operative position in the channel of said slider body.

8. A lock slider for separable fasteners, said slider comprising a channeled body having walls spaced at the wide end of said body by a connecting frog forming diverging channels at the wide end of said body, a lock element movably supported in the frog of said slider to extend into the channel thereof at the intersection of said diverging channels, a spring mounted in the slider and engaging said element to normally hold the said element in projected operative position in the channel of said slider body, opposed walls of the slider having elongated apertures in alignment with said frog, and said element having end portions projecting beyond the channel of the slider into, and operating in, the apertures of said slider walls.

9. A separable fastener of the class described, comprising stringers coupled and uncoupled by a slider movable along the stringers, said stringers having scoops with coupling portions projecting from one edge thereof, a slider movable along the scoops of both stringers to couple and uncouple the same, a lock element on the slider arranged to engage a scoop between the side walls thereof to check movement of the slider in one direction on the stringers, and a spring located between the side walls of the slider and adapted to hold the locking element in operative position.

10. A slider for separable fasteners having top and bottom walls spaced and connected by a web portion, said walls and web portion partly defining a pair of channels converging into a single channel having an axis coinciding with the longitudinal axis of the slider, said slider being adapted to couple and uncouple opposed series 70 of scoops mounted on stringers, said scoops having side portions in juxtaposition to the said slider walls; a lock element arranged transversely of the slider; means mounting the element for movement longitudinally of the slider and into 75

engagement with the scoops at points between the said side portions thereof, and for movement out of said engagement; resilient means urging the lock element longitudinally of the slider into engagement with the scoops; and pull means to release the element from said engagement.

11. A separable fastener of the class described, comprising stringers coupled and uncoupled by 10 a slider movable along the stringers, said stringers having scoops with coupling portions projecting from one edge thereof, outer ends of the coupling portions of the scoops having projecting members, a slider movable along the scoops of 15 both stringers to couple and uncouple the same, said slider having top and bottom walls spaced and connected by a web portion, said walls and web portion partly defining a pair of channels converging into a single channel having an axis coinciding with the longitudinal axis of the slider; a lock element arranged transversely of the slider; means mounting the element for movement longitudinally of the slider and into engagement with the scoops at points between the said side 20 portions thereof, and for movement out of said engagement; resilient means urging the lock element longitudinally of the slider into engagement with the scoops; and pull means to release the element from said engagement.

12. A slider for separable fasteners having top and bottom walls spaced and connected by a web portion, said walls and web portion partly defining a pair of channels converging into a single channel having an axis coinciding with the longitudinal axis of the slider, said slider being 30 adapted to couple and uncouple opposed series of scoops mounted on stringers, said scoops having side portions in juxtaposition to the said slider walls; one of said walls having an aperture therein elongated longitudinally of the slider, said aperture being defined by edge portions; an elongated lock element arranged transversely of the slider and extending through said aperture and having an end extending beyond said wall of the slider adjacent said aperture, said lock element being slidably and pivotally mounted in relation to each of said slider walls; means in each of said slider walls including edges of said aperture, providing a pivot for the rocking movement of said element and a bearing to guide and limit the sliding and rocking movement of said element; resilient means mounted within the boundaries of said slider walls and urging said lock element longitudinally of the slider into engagement with said scoops; and pull means connected to said end of the lock element to swing said element about each of said pivots against the urge of said resilient means to release said element from locking engagement with said 40 scoops.

13. A slider for separable fasteners having top and bottom walls spaced and connected by a web portion, said walls and web portion partly defining a pair of channels converging into a single channel having an axis coinciding with the longitudinal axis of the slider, said slider being 50 adapted to couple and uncouple opposed series of scoops mounted on stringers, said scoops having side portions in juxtaposition to the said slider walls; said walls having transversely aligned apertures therein elongated longitudinally of the slider, said apertures being defined by edge portions; an elongated lock element arranged transversely of the slider and within said apertures, said element extending beyond one of

said slider walls and having an end portion adjacent thereto, edge portions of said apertures providing means pivotally and slidably mounting the lock element in each of said slider walls; resilient means slidably urging the lock element into locking engagement with said scoops; and pull means connected to said end portion of the lock element to swing said element about each of said pivots against the urge of said resilient means to release said element from said locking engagement.

14. A slider for separable fasteners having top and bottom walls spaced and connected by a web portion, said walls and web portion partly defining a pair of channels converging into a single channel having an axis coinciding with the longitudinal axis of the slider, said slider being adapted to couple and uncouple opposed series of scoops mounted on stringers, said scoops having side portions in juxtaposition to the said slid-

er walls, said walls having transversely aligned apertures therein elongated longitudinally of the slider, said apertures being defined by edge portions; an elongated lock element arranged transversely of the slider and within said apertures, said element extending beyond each of said slider walls and having end portions adjacent said apertures, respectively; edge portions of said apertures providing means pivotally and slidably mounting the lock element in each of said slider walls; resilient means slidably urging the lock element into locking engagement with said scoops; and pull means connected to each of said end portions of the lock element to swing said element about each of said pivots against the urge of said resilient means to release said element from said locking engagement.
